UNITED STATES PATENT OFFICE.

PETER RAU, OF SAARLOUIS, GERMANY.

PUNCH FOR MAKING CENTRALLY-PERFORATED WASHERS.

1,109,596.

Specification of Letters Patent.

Patented Sept. 1, 1914.

Application filed March 5, 1914. Serial No. 822,622.

To all whom it may concern:

Be it known that I, PETER RAU, a subject of the German Emperor, and resident of Saarlouis, Germany, have invented certain new and useful Improvements in Punches for Making Centrally-Perforated Washers, of which the following is a specification.

This invention relates to an improved punch for making centrally perforated washers, of the kind having two concentric cutters and a resiliently mounted ejector, the novelty consisting in a removable arrangement of the inner cutter on the ejector, which is adjustable within certain limits, whereby upon a little yielding at the same time the inner and the outer cutter engage the material for punching the outer circumference as well as the central hole, so that any distortions produced by a non-simultaneous engagement of the cutters with the material are avoided.

The accompanying drawing shows the subject matter of the invention.

The punch comprises a handle *a* for the reception of the head *b*. In the latter an automatic ejector is located, which consists of an ejection disk *i* with guiding-bolt *e* screwed therein, the bolt being engaged by a spring *f*. In the ejection disk a conical boring is provided for keeping the cutter *g* in place.

The device is held by a set-screw *d* in the head, a screw *c* connecting the handle with the head. The improved punch can work with the handle thereon only. The opera-

tion is such that, upon the cutting edge of the head having cut the outer circumference of the washer, the ejector presses the spring back, until the guiding-bolt bears with its rear end against the abutment *m* in the boring of the handle *a*. By the resistance and further pressure, the punching out of the central hole of the washer is effected by the cutter *g*. According to the thickness of the material, and particularly for india rubber, 45 regulating rings must be inserted between the guiding-bolt *e* and abutment *m*. Paper and non-elastic material may be folded several times, and a plurality of washers can thus be punched at a time. The waste material cut out escapes through the boring in the guiding-bolt and the opening *h* in the handle. Upon the spring being untensioned, the finished washer is automatically ejected. The cutter *g* may vary in size and cross- 50 section, so as to punch washers with different central holes therein.

What I claim, is:

In a punch for making centrally perforated washers, the combination of a resiliently mounted automatic ejector, means to limit the extent of movement of the latter, and two concentric cutters, the inner one being removably fixed to and movable with said ejector, substantially as and for the purpose set forth.

PETER RAU.
